(57) **CLAIM**

The ornamental design for a watering device as shown and described.

DESCRIPTION

FIG. 1 is a first top perspective view of a first embodiment of a watering device, according to my new design;

FIG. 2 is a second top perspective view of the first embodiment of the watering device;

FIG. 3 is a first bottom perspective view of the first embodiment of the watering device;

FIG. 4 is a second bottom perspective view of the first embodiment of the watering device;

FIG. 5 is a front elevational view of the first embodiment of the watering device;

FIG. 6 is a rear elevational view of the first embodiment of the watering device;

FIG. 7 is a top plan view of the first embodiment of the watering device;

FIG. 8 is a bottom plan view of the first embodiment of the watering device;

FIG. 9 is a left side elevational view of the first embodiment of the watering device;

FIG. 10 is a right side elevational view of the first embodiment of the watering device; and,

FIG. 11 is a top perspective view of a second embodiment of the watering device, noting that the claimed portion of the first embodiment is identical to the claimed portion of the second embodiment.

The dash-dash broken lines in the figures are included for the purpose of depicting unclaimed portions of the watering device and form no part of the claimed design. The dot-dash broken lines in the figures are included for the purpose of depicting a boundary between a claimed portion and an unclaimed portion of the watering device and form no part of the claimed design.
